UNITED STATES PATENT OFFICE.

EDWARD CHESHIRE, OF PITTSBURGH, PENNSYLVANIA, ASSIGNEE TO MILLER SAW TRIMMER COMPANY OF MICHIGAN, OF PITTSBURGH, PENNSYLVANIA, A CORPORATION OF MICHIGAN.

SHEET SEPARATING AND MOVING DEVICE.

1,194,327.

Specification of Letters Patent. Patented Aug. 8, 1916.

Application filed September 13, 1913. Serial No. 790,526.

To all whom it may concern:

Be it known that I, EDWARD CHESHIRE, a citizen of the United States, residing at Pittsburgh, in the county of Allegheny and State of Pennsylvania, have invented new and useful Improvements in Sheet Separating and Moving Devices, of which the following is a full, clear, concise, and exact description, reference being had to the accompanying drawing, forming a part of this specification.

My invention pertains to sheet separating and moving devices, and relates especially to mechanism for separating the top sheet from the remainder of a pile of sheets and lifting it into a position whence it can be readily taken away by a sheet removing device.

It is the principal object of my invention to provide a device of the above character which will be of a simple construction, the parts of which are not liable to get out of order, and which will operate with certainty and precision.

It is another object of my invention to improve upon the existing forms of suction foot, and to provide one which will operate efficiently and with certainty, and which will not pick up more than one sheet at a time.

Other and further objects of my invention will appear from the following description taken in connection with the appended claims.

As an example of an embodiment of my invention, a sheet separating and moving device constructed in accordance therewith is described in the following specification and shown in the accompanying drawings, as applied to a paper feeding and handling device of the kind disclosed in my co-pending application, Serial No. 790,525 filed Sep. 18, 1913. I wish it to be understood, however, that the device may be used in other connections than that in which it is described and shown, and that changes may be made in the mechanism described and shown without exceeding the scope of my invention as defined in the appended claims.

In the drawings: Figure 1 is a plan of a paper feeding and handling device of the kind disclosed in my co-pending application above referred to, to which the sheet separating and moving device, hereinafter described and shown, is applied; Fig. 2 is a

section on the line 2—2 of Fig. 1, showing the principal parts of the sheet separating and moving device in side elevation and vertical section; Fig. 3 is an inverted plan of the hood of the paper feeding and handling device, the latter being shown as swung upward about its hinge, disclosing, in inverted plan, the principal portions of the sheet separating and moving device; Fig. 4 is a detached rear view of the separator bar; Fig. 5 is a plan of the same; Fig. 6 is a central section through the vacuum controlling valve; Fig. 7 is a vertical section through one of the stock guides; Fig. 8 is a horizontal section taken on the line 8—8 of Fig. 7, looking in the direction of the arrows; Fig. 9 is an enlarged front elevation of the center suction foot; Fig. 10 is a section on the line 10—10 of Fig. 9; Fig. 11 is an inverted plan of the foot shown in Fig. 9; Fig. 12 is a view similar to Fig. 10, but on a larger scale, showing the operation of the suction foot on a sheet of paper; Fig. 13 is a fragmentary view seen from the line 13—13 of Fig. 12, looking in the direction of the arrows; Fig. 14 is a plan of a side suction foot having its lower face formed similarly to the foot shown in Figs. 9—11; Fig. 15 is an inverted plan of the suction surface of a foot especially adapted for use in connection with very thin paper; Fig. 16 is a sectional elevation of the same, the section being taken on the line 16—16 of Fig. 15; Fig. 17 is a front elevation of a suction foot especially adapted for use with heavy paper; Fig. 18 is an inverted plan of the same; Fig. 19 is a section on the line 19—19 of Fig. 18; Fig. 20 is a view of a portion of Fig. 19, drawn to a larger scale, showing the operation of the suction foot upon a sheet of paper; and Fig. 21 is a fragmentary view seen from the line 21—21 of Fig. 20, looking in the direction of the arrows.

Like reference characters refer to like parts throughout the following specification and the several figures of the accompanying drawings.

As has been stated above the present embodiment of my invention is described as applied to a paper feeding and handling device of the kind disclosed in my co-pending application above referred to. Such a paper feeding and handling device includes a feed box 30 which is secured to the rear portion

of the frame 31 of a platen press, so that the front portion of the feed box is in proximity to the rear portion of the platen 32 of the press when the latter is in its stationary position out of parallelism with the form-receiving bed. To the feed box 30 is hingedly connected a hood 33, which may be swung upward about its hinge when desired. The hood 33 carries a feed frame 34 which is adapted to be moved toward and away from the feed box 30, over the platen 32, when the latter is in its stationary position out of parallelism with the bed. The feed frame 34 carries grippers 35 which are adapted, at every cycle of the mechanism, to seize a sheet which has been separated and lifted by the mechanism hereinafter to be described. The feed box 30 contains a floating stock table 36 which is adapted to be automatically raised as the sheets of paper are removed therefrom, such raising being effected by a table elevating mechanism of the kind which is disclosed in my co-pending application, Serial No. 790,524, filed Sept. 18, 1913.

Briefly, the construction of the table elevating mechanism is as follows: The stock table 36 is provided with a pillar 37 which is supported in the feed box 30 so as to be capable of a vertical sliding movement. This table, when released, is moved upward by means of a spring 38 which operates upon the table through link mechanism. A clutch, having a roller 39, normally locks the pillar 37 so as to hold the stock table 36 stationary. This clutch is adapted to be released, once during every cycle of the press, by a cam projection 40 which extends from the press shaft 41, and during the rotation of the shaft 41, strikes the roller 39. When the cam projection 40 strikes the roller 39 the table 36 is released, and can be moved upward by the spring 38.

The feed box 30 is provided with a transverse guide 42 upon which are slidably mounted a pair of side stock guides 43 which project upwardly through suitable slots in the stock table 36. The stock guides 43 are apertured and threaded to receive screws 44 which project rearwardly so as to be accessible at the back of the feed box. The screws 44 engage against the transverse guide 42 so as to lock the stock guides 43 in any position to which they may be adjusted on the guide 42. By loosening the screws 44, the stock guides 43 may be shifted in one direction or the other upon the transverse guide 42 in accordance with the width of the stock on the stock table. When thus adjusted, the stock guides 43 may be locked in place by tightening the screws 44. The stock table 36 is provided with a longitudinally adjustable vertical rear stock guide 45.

The hood 33 is provided at opposite sides thereof, with inwardly extending lugs 46

(Figs. 2, 3, 4 and 5) in which are slidably mounted pins 47 which extend upwardly from the ends of a transverse separator bar 48. The pins 47 are engaged by the ends of a pair of lifting levers 49, which are secured to a rock shaft 50 extending transversely across the hood 33. One of the lifting levers 49 is provided with a cam roller 51 which is held, by a spring 52 wound upon the shaft 50, in engagement with a cam 53 keyed to the main feed shaft 54. As the main shaft 54 revolves the cam 53 presses the separator bar 48 downwardly into engagement with the top sheet of the pile of stock carried by the table 36, holds it for a short time in engagement with such sheet, subsequently permits it to be raised under the action of the spring 52, and subsequently allows it to remain stationary for a short time in its raised position. The separator bar 48 carries a center pneumatic foot 55 and a pair of side pneumatic feet 56, which feet attach to themselves the top sheet of the pile of stock when the separator bar is depressed and carry such sheet with them when the separator bar is subsequently raised again. The pneumatic feet 55 and 56 are mounted on the separator bar so as to be adjustable thereon for different sizes of paper and positions of the pile of stock, and will ordinarily be arranged so that the center foot engages the sheets from the front edge rearward, and the side feet engage the sheet from the side edges, somewhat to the rear of the front edge, inward (Fig. 5).

Referring now particularly to Figs. 2, 3 and 6, a suction controlling valve 57 is provided for applying suction to the pneumatic feet and relieving the feet from suction at the proper times. Such controlling valve includes a casing 58 (Fig. 6) having two chambers 59 and 60 formed therein, of which the chamber 59 is connected, by a hose 61, with a suitable source of vacuum, and the chamber 60 is connected, by a hose 62, with the pneumatic feet. A passage 63 normally connects the chambers 59 and 60. Slidably mounted in the casing 58 is a valve member 64 provided with an enlargement 65 adapted to close the passage 63 when the valve member is moved rearward. The valve member is also provided with a head 66 which normally closes the chamber 60, but opens such chamber to the atmosphere when the valve member 64 is moved rearward. When, therefore, the valve member 64 is in the position shown in Fig. 6, the chamber 59 is in communication with the chamber 60, which is closed. Suction is consequently communicated to the pneumatic feet. When, however, the valve member 64 is moved rearward, as indicated in Fig. 2, the chamber 59 is cut off from the chamber 60 and the chamber 60 is opened to the atmosphere, the pneumatic feet being thus relieved from

suction and put into communication with the atmosphere.

The valve member 64 is normally held in the position shown in Fig. 6 by a spring 67 which is wound about the casing 58 and engages a cross-pin 68 at the end of the valve member. Rotatably mounted on the pin 68 is a cam roller 69 which engages a cam 70 secured to the main shaft 54. When the cam 70 strikes the roller 69 the valve member 64 is forced rearwardly against the action of the spring 67, whereby the pneumatic feet are released from vacuum and put into communication with the atmosphere. This occurs just after the lifted sheet has been seized by the grippers 35, whereby the grippers are permitted to remove the sheet in the manner described in my co-pending application, Serial No. 790,525 above referred to. Shortly after the sheet has been removed, the cam 70 moves out of engagement with the roller 69 and permits the valve member 64 to be moved forward by the spring 67, whereby suction is again applied to the pneumatic feet. This occurs prior to the time at which the feet have been moved into engagement with the top sheet of the pile of stock.

The operation of the mechanism so far described is as follows: When the separator bar first reaches its uppermost position, carrying with it a sheet of paper, the controlling valve 57 is in the condition shown in Fig. 6, the vacuum at the pneumatic feet holding the sheet in position thereagainst. Immediately afterward, the grippers 35 seize the sheet and the cam 70 relieves the pneumatic feet from vacuum, the sheet being then held in its raised position by the grippers. The feed frame 34 then carries the sheet forward over the platen. After this has occurred, the separator bar remains stationary for a short time and then starts to descend. As the separator bar begins to descend, the controlling valve 57 is permitted to return to the condition shown in Fig. 6, so that the separator bar reaches the paper with the pneumatic feet under suction. After the separator bar has reached its lowermost position the cam projection 40 releases the clutch and permits the stock table, under the action of the spring 38, to press the stock against the lower faces of the pneumatic feet, the upward movement of the stock table being substantially equal to the thickness of the sheet removed during the previous cycle of the mechanism. After this upward movement has occurred, and before the separator bar rises again, the cam projection 40 has passed away from the roller 39, whereby the stock table is locked again. The pneumatic feet attach to themselves the top sheet of the pile of stock and carry the sheet with them when the separator bar is raised again. When the separator bar

reaches its uppermost position, the sheet is taken away by the grippers 35 in the manner described above.

In order to aid in the separation of the top sheet from the second sheet of the pile, means are provided for blowing a current of air against the edges of the top few sheets of the pile. In the embodiment now being described this is effected by making the side stock guides 43 hollow and connecting them with a suitable source of air under pressure. As a convenient source of air under pressure the exhaust of a vacuum pump, the intake of which is connected with the hose 61, may be employed. As clearly shown in Figs. 7 and 8 the stock guides 43 are made in the form of flat tubes closed throughout their length and each having an opening 71 adjacent the top of its inner face, which opening will be in proximity with the top few sheets of the pile of stock, when the stock is in proper position with respect to the separator bar. The two stock guides are each provided with a hose connection which carries a hose 72 connected, as has been said, with a suitable source of air under pressure. It will be seen that the air blows out of the apertures 71 against the side edges of the top few sheets of the pile of stock, slightly separating them and interposing a film of air between each sheet, whereby the separation is materially aided.

In order that the suction at the pneumatic feet may be varied according to requirement, I provide a bleeding valve 73 in the hose 61 which valve opens to the atmosphere. By manipulating the valve 73 the degree of suction at the pneumatic feet may be altered in accordance with the nature of the paper being operated upon. Likewise, a bleeding valve 74 is provided in the hose 72, by manipulating which the amount of air issuing from the apertures 71 may be varied as desired. In order that the operation of the mechanism may be quickly stopped at will, a shut-off valve 75 is provided in the hose 61.

The pneumatic feet ordinarily employed are of the kind shown in Figs. 9-14. It has been found that these feet will answer perfectly for all papers within a wide range of variation as to thickness and stiffness. For paper of exceptional thinness, a pneumatic foot of the type shown in Figs. 15 and 16 has been found to operate satisfactorily; and, for paper of exceptional thickness, a pneumatic foot of the type shown in Figs. 17-20 is ordinarily employed.

Referring now particularly to the pneumatic feet shown in Figs. 4 and 5 and 9-14, the center foot 55 (Figs. 9-11) consists of a metallic block 76 having formed therein a transverse channel 77 for receiving the separator bar 48. The block 76 is provided with a rearwardly extending securing screw 120

78 which is adapted to engage in a groove formed in the rear face of the separator bar 48. It will be seen that, by loosening the screw 78, the foot 55 can be adjusted 5 to any desired position upon the separator bar; and, when it has been adjusted, it can be secured in position by tightening the screw 78 again. The lower face of the block 76 is formed with a suction chamber 79 10 with which communicates two pieces of hose. One of these is a hose 62 communicating with a vacuum control valve (not shown); and the other is a hose 80 which communicates with the diaphragm box for 15 operating the throw-off mechanism, as described in my co-pending application, Serial No. 790,525 above referred to.

A plate 81 is secured to the lower face of the block 76 so as to form a cover for 20 the chamber 79. The plate 81 is curved longitudinally of the block 76 and is formed with a plurality of transverse channels 82 which communicate with the chamber 79 by means of apertures 83. The transverse 25 channels 82 do not connect with each other, and they terminate short of the front and rear edges of the plate 81, a plurality of sealing surfaces 84, between the channels, and sealing lips 85 at the front and rear 30 of the channels, being thus provided. The sealing lips are made substantially flat, as shown, and preferably tangential to the curve of the intermediate surfaces 84. The plate 81 is so formed and disposed that 35 the sealing surfaces 84 are upon the same plane as the bottom surface of the block 76. At the rear of the plate 81, the block 76 is formed with a channel 86 which extends transversely of the block and longitudinally 40 of the plate 81.

When the pneumatic foot 55 is in position upon the top sheet of a pile of paper, suction being present in the chamber 79, the top sheet of the pile, designated 87 in Figs. 45 12 and 13, is sucked up against the lower surface of the foot. In being drawn upward, the sheet is bent so as to seal against the curved surfaces 84. In being thus bent, its portions at the front and rear of the surfaces 84 are brought into flat engagement with the lips 85. The necessity of bending the paper, except at the part which engages the surfaces 84 is thus avoided, and a perfect sealing obtained without employing a 50 high degree of vacuum. When the top sheet 87 thus seals itself against the lips 85 and intermediate surfaces 84, the channels 82 become, in effect, a plurality of suction chambers, into which chambers the top sheet 87 is partly sucked, as indicated in 55 Figs. 12 and 13. The sucking of the sheet into the channels 82 thus creates a plurality of small passages as indicated at 98 in Figs. 12 and 13. The passages 98 extend from 60 the outer edge of the paper inward, be-

tween the top sheet 87 and the second sheet 88, and open, at their inner ends, into a transverse chamber 99, which is formed between the sheets 87 and 88, by reason of the sheet 87 being sucked up into the transverse 70 channel 86. By reason of the formation of this chamber 99 between the top sheet and the second sheet, into which air can flow through the passages 98, it is insured that air in quantity be admitted between the top 75 sheet and the second sheet of the pile.

Suction feet for separating paper, as heretofore constructed, have been subject to the disadvantage that the foot would often lift more than one sheet at a time. This was largely due to the fact that vacuum spaces were formed, between the top and second sheets, at the parts close to the edges of the suction opening of the foot, the formation of these spaces being due to leakage of air, through the top sheet, into the suction opening of the foot. In the case of the foot described above, the formation of such vacuum spaces between the top and second sheets is avoided, air being admitted between 90 the sheets, not only beneath the suction channels, but at all the parts surrounding them. The space 99 and the space 100 beneath the front edge of the foot, together 95 form a chamber, in communication with the atmosphere, which embraces the suction channels and surrounds the same except for the negligibly small portions engaged by the surfaces 84. The center foot 55 engages the paper from the front edge thereof rearwardly. The two side feet 56 engage the paper from the side edges thereof, somewhat to the rear of the front edge (Fig. 5), inwardly. One of the side feet is shown in 100 Fig. 14. So far as the suction chamber 79 105 and the lower surface of the foot are concerned, the foot 56 is similar to the foot 55. There is, however, only one hose provided, being the hose 62 which communicates with the vacuum control valve. The channel 110 which receives the separator bar 48 is, in the case of the foot 56, disposed longitudinally with respect to the suction channels 82 instead of transversely, as is the case in the foot 55. The foot 56 operates in the same 115 manner as does the foot 55.

The pneumatic foot for use with very thin paper (Figs. 15 and 16) is of the same general construction as that disclosed in Figs. 9-11, and is provided with a plate 89 and a channel 90 corresponding to the plate 81 and the channel 86 of the foot 55. The suction channels 91, however, are in this case made more numerous and relatively deeper than are the channels 82, this being desirable for the reason that the thin paper can be distorted more readily to take the shape of the channel than can the ordinary thicknesses of the paper which are handled by the foot 55. The operation of the pneumatic 120 125 130

foot shown in Figs. 15 and 16 is the same as that of the foot shown in Figs. 9-13.

The pneumatic foot shown in Figs. 17-21, which is intended for use with exceptionally heavy paper, differs from the pneumatic feet described above in that there is only one air chamber formed between the top sheet and the sheet next succeeding it. This has been found to be sufficient where 10 heavy paper is being used. The suction foot shown in Figs. 17-21 includes a block 93 having formed therein a channel for receiving the separator bar 48, and being provided with a locking screw 94 for securing the foot 15 to the separator bar in any desired location. The lower surface of the block 93 is flat except for a concave depression 95 which is formed near the front part thereof. The depression 95 opens at the front of the foot and is curved downward rearwardly so as to merge into the flat portion of the foot near the center of the latter; and it is also curved laterally of the foot, as clearly shown in Figs. 17, 18 and 19. At the bottom of the 20 depression 95 are formed a plurality of intersecting grooves or channels 96 which communicate with each other, and into which opens a port 97. Into the port 97 open the two hose 80 and 62, of which the hose 80 is 25 connected with the diaphragm and the hose 62 connected with the vacuum control valve, as described in connection with the foot shown in Figs. 9-13.

It will be seen that when vacuum is applied to the foot the grooves 96 form a plurality of small suction spaces, against which the top sheet 87 is drawn. The top sheet is thus brought into engagement with the lower face of the depression 95, thereby being buckled to the shape of this depression. This buckling of the top sheet, which is clearly illustrated in Figs. 20 and 21, causes an air chamber of considerable size to be produced between the top sheet 87 and the second sheet 88, the pneumatic foot being thus prevented from raising two or more sheets at a time.

Having thus described my invention, what I claim as new and desire to secure by Letters Patent is:

1. Mechanism for separating sheets one by one from a pile of stock comprising a separator bar disposed transversely above the front portion of the pile and vertically 55 movable with respect thereto, a suction foot adjustably carried by said separator bar and adapted to engage from the front edges of the sheets rearwardly, a pair of suction feet 60 adjustably carried by said separator bar and adapted to engage the sheets from the side edges thereof inwardly, and means for moving said separator bar toward the pile to permit said feet to receive a sheet therefrom, and subsequently moving it away from said 65 pile, for the purposes set forth.

2. Mechanism for separating sheets one by one from a pile of stock comprising a support, vertical guides carried by said support, a separator bar slidably mounted in said guides, a spring-retumed lever for operating said separator bar, a cam shaft, a cam carried by said shaft for actuating said lever, a suction foot carried by said separator bar, a controlling valve for said suction foot, and a second cam carried by said shaft 75 for actuating said controlling valve.

3. Mechanism for separating sheets one by one from a pile of stock comprising a support, vertical guides carried by said support, a separator bar slidably mounted in said 80 guides, a spring-retumed lever for operating said separator bar, a cam shaft, a cam carried by said shaft for actuating said lever, a plurality of suction feet carried by said separator bar, a valve for controlling all of said 85 suction feet, and a second cam carried by said shaft for actuating said controlling valve.

4. A suction foot for separating the top sheet from the remainder of a pile of stock, 90 said foot having a suction opening in the lower side thereof and having such lower side formed to prevent the creation of vacuum spaces between the top and second sheets, at the parts of such sheets embracing said 95 suction opening.

5. A suction foot for separating the top sheet from the remainder of a pile of stock, the lower surface of said foot having a suction opening therein and being formed to 100 create, between the first and second sheets, an air chamber embracing the edge of said opening and in communication with the atmosphere.

6. A suction foot for separating the top 105 sheet from the remainder of a pile of stock, the lower surface of said foot having a suction opening therein and being formed to create, between the first and second sheets, an air chamber embracing the edge of said 110 opening and in communication with the atmosphere, and a second chamber beneath said opening and in communication with the atmosphere.

7. A suction foot for separating the top 115 sheet from the remainder of a pile of stock, said foot having the lower part thereof formed with a convex surface having a suction opening therein, said surface and opening being formed so as to create, between the 120 top and second sheets of the pile, an air chamber at the rear of said surface, and a second air chamber communicating with the atmosphere and with said first-named air chamber.

8. A suction foot for separating the top sheet from the remainder of a pile of stock, 125 said foot having the lower part thereof formed with a convex surface having a plurality of suction openings therein, said sur-

face and openings being formed so as to create, between the top and second sheets of the pile, an air chamber at the rear of said surface and a plurality of air chambers communicating with the atmosphere and with said first-named air chamber.

In witness whereof, I have hereunto sub-

scribed my name in the presence of two witnesses.

EDWARD CHESHIRE.
